UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

AUTOMATIC SELECTIVE SWITCH.

1,251,988.

Specification of Letters Patent.

Patented Jan. 1, 1918.

Application filed November 15, 1916. Serial No. 131,456.

To all whom it may concern:

Be it known that I, JAMES L. MCQUARRIE, a citizen of the United States, residing at Montclair, in the county of Essex and State 5 of New Jersey, have invented certain new and useful Improvements in Automatic Selective Switches, of which the following is a full, clear, concise, and exact description.

This invention relates to automatic selective switching devices of the type which are 10 actuated by some mechanical means, and more particularly to the controlling means for such switches.

In accordance with the principal feature 15 of this invention, there is associated with the automatic switching device a mechanism in which is combined both electrical and mechanical control features. Preferably this mechanism comprises a sequence switch operating in its usual capacity as a circuit controlling device, and being adapted, in addition, to mechanically control devices which in turn control the starting, stopping and release of the automatic switching device. 20 The mechanical functions of the sequence switch may be attained through the use of cams mounted upon the sequence switch shaft, and operating in certain positions of the shaft to perform the desired functions.

30 In the drawings in which this invention is illustrated in connection with a fluid operated switch, Figure 1 is a view in side elevation with parts in section of a switching device with the controlling mechanism of this invention applied thereto; and Fig. 2 is a diagram of a circuit illustrating the application of this invention to a telephone system.

It is thought the invention may best be 40 understood by the following detailed description.

Referring now especially to Fig. 1, T represents a bank of terminals, and B represents a set of brushes arranged to travel 45 over and make contact with these terminals. The brushes B are mounted on a shaft S connected with the driving means of the selector switch. The lower part of the shaft S is provided with notches N, the function 50 of which will be described later. Connected to the shaft S, is a piston rod PR, which in turn is directly connected to the piston P,

movable in the cylinder C. An aperture A is provided for leading compressed air from some source or storage tank to the switch. 5 Communication between the aperture A and the cylinder C is had through a valve V¹, when opened, and a port 1. The valve V¹ is controlled through a shaft 2 and a lever 3. An exhaust valve V² gives communication between the port 1 and the outside of the apparatus for the purpose of exhausting the compressed air under the piston and allowing the brush carriage to descend. The valve V² is controlled through 60 65 the hollow shaft 4 and the lever 5.

Made a part of and supported by the same frame as that which supports the cylinder of the selective switch, but not shown here, is a step-by-step sequence switch. This 70 switch is operated by its magnet M through a pawl 6 and a ratchet wheel 7. The movement of the ratchet wheel 7 causes the rotation of the spindle 8, which in turn actuates the two contactors 9 and 10. Securely fastened to the spindle 8 are four cams, 11, 12, 13 and 14. These cams control the movements of the levers 3, 5, 15 and 16, whereby the intake and exhaust valves of the switch are actuated. It should be noted that levers 80 15 and 16 operate valves similar to V¹ and V² and control the ingress and egress of compressed air to the portion of the cylinder above the piston C.

A magnet RM is rigidly connected to the 85 frame, and controls a pawl 17 which, working in the notches N, holds the brushes B immovable on a selected contact T. This is provided to prevent the movement of the brushes B should there be any leaks in the 90 cylinder C.

Referring now especially to Fig. 2, we 95 may assume that a call has been initiated by a subscriber, answered by a semi-automatic exchange operator and that said operator has, by means of a cord circuit, connected a sender to this local incoming circuit. A sender suitable for use in this connection is fully described in patent to Lundell No. 1,168,319.

Upon the seizure of this local incoming circuit, a fundamental circuit will be established from grounded battery, the sequence switch contact 101, sequence switch contact

100

102, resistance R^1 , conductor 50 and thence to the conductor 51 through the apparatus of the sender, sequence switch contact 103, sequence switch contact 104, resistance R^2 to ground. Relay 52 is energized in this circuit and completes a locking circuit for itself from grounded battery, the winding of relay 52, the contact and left-hand armature of relay 52, sequence switch contact 105 and thence through the circuit previously traced. At its right-hand armature relay 52 completes a circuit which extends from ground, sequence switch contact 106, the right-hand armature and alternate contact of relay 52, the sequence switch contact 107, the winding of magnet 53 to battery and thence to ground. Relay 53 is thereby energized and in turn completes a circuit from ground, its right-hand armature and alternate contact, sequence switch contact 108, sequence switch contact 109 to the motor magnet 100 of the sequence switch, interrupter I, to battery and thence to ground. The motor magnet makes one step and moves its contactors into position 2. As the contactors move out of position 1, the circuit for energizing the motor magnet 100 is broken at the sequence switch contact 108.

Relay 53 will be maintained in an energized condition through a circuit leading from a ground in the cord circuit which has seized this selector circuit, as indicated by the numeral 110, the resistance R^4 , the left-hand armature and alternate contact of relay 53, the winding of relay 53 to battery and thence to ground.

As the sequence switch passes out of position 1 and into position $1\frac{1}{2}$, a circuit is prepared for shunting out the stepping relay of the sender, which extends from the sequence switch contact 105 to the sequence switch contact 111, and thence to the commutator segment 54, where it will later be extended through the brush B^2 to ground. As position 2 is reached, valve-operating levers 112 and 113 cause the opening of the intake valve leading to the chamber below the piston, and the exhaust valve leading to the chamber above the piston, respectively. The compressed air beneath the piston P forces it upward, and, as the brush B^2 passes over the commutator segment 54, the stepping relay of the sender is intermittently short-circuited and will thereby be caused to retract and attract its armature until the sender is satisfied, at which time the fundamental circuit will be opened, whereupon the relay 52 will retract its armatures.

The retraction of the armatures of the relay 52 completes a circuit from ground, sequence switch contact 106, the right-hand armature and normal contact of relay 52, the left-hand armature and normal contact of relay 55, sequence switch contact 109, winding of motor magnet 100 of sequence switch,

interrupter I, battery and thence to ground, whereupon the sequence switch will take one step forward and move its contactors into position 3. The circuit for energizing the motor magnet 100 just described will be opened as the contactors of the sequence switch leave position 2 at the sequence switch contact 114.

In this position the trip magnet TM is energized over a circuit leading from ground, battery, the winding of trip magnet TM, sequence switch contact 115, sequence switch contact 116, to ground. The trip magnet operates to release the particular set of brushes selected in a manner similar to that described in U. S. Patent 1,177,044.

The sender having been satisfied at the conclusion of the sending of the brush selecting impulses, mechanism described in the patent to Lundell 1,168,319 now acts to close the fundamental circuit, whereby the relay 52 is again energized and again completes a locking circuit for itself over its contact and left-hand armature as before described. Upon attracting its armatures, relay 52 completes a circuit from ground, sequence switch contact 106, the right-hand armature and alternate contact of relay 52, the sequence switch contact 117, sequence switch contact 118 to the magnet 100 of the sequence switch, interrupter I, battery, and thence to ground, whereupon sequence switch 100 steps its contactors into position 4.

In position 4 the valve-operating cams 112 and 113 again allow compressed air to flow into the cylinder of the pneumatic switch, whereupon the brush carriage B is again elevated. Brush B^1 now passes over the commutator segment 56, and thereby intermittently shunts out the stepping relay 105 of the sender over a circuit from ground, brush B^1 , commutator segment 56, sequence switch contact 119, to a junction with the fundamental circuit.

When the sender is again satisfied, a particular group of terminals T have been selected. The relay 52 becomes deenergized, and upon the retraction of its armature, completes a circuit from ground, sequence switch contact 106, the left-hand armature and alternate contact of relay 55, sequence switch contact 114, sequence switch contact 109, to the motor magnet 100 of the sequence switch, interrupter I, battery and thence to ground. Sequence switch 100 moves its contactors into the fifth position, and, in so doing, opens the circuit just described at the sequence switch contact 114.

In the fifth position, a circuit is established from ground, sequence switch contact 116, sequence switch contact 120, right-hand winding of relay 55 to battery and thence to ground. Relay 55 attracts its armatures and thereby prevents the grounding of brush B^5 at this time through a circuit

which would otherwise extend from ground, sequence switch contact 123, normal contact and right-hand armature of relay 55, resistance R^3 to brush B^5 .

5 When the sender was satisfied after the sending of the group selecting impulses, the relay 52 was deenergized, and retracting its armatures, established a circuit from ground, sequence switch contact 106, the armature 10 and alternate contact of relay 55, sequence switch contact 117, sequence switch contact 118, motor magnet 100 of the sequence switch, interrupter I, battery, and thence to ground. The sequence switch moves its contacts into the sixth position, and in so doing, opens the circuit just described at the sequence switch contact 117.

20 In position 6 the valve-operating levers 112 and 113 again allow the ingress of compressed air below the piston P, whereby the brush carriage B is again elevated.

25 In this position, relay 55 is maintained in an energized condition over a circuit extending from ground, brush B^3 , commutator segment 57, sequence switch contact 121, sequence switch contact 120, the right-hand winding of relay 55 to battery and thence to ground. As brush B^3 moves on to an insulated section of commutator segment 57, the brush B^5 is positioned on a terminal t^1 . If 30 this terminal is connected with a busy trunk, it will be grounded in a manner well-known in the art, and hence relay 55 will be maintained energized over a circuit extending from the ground leading to the terminal t^1 , brush B^5 , resistance R^3 , right-hand armature and alternate contact of relay 55, sequence switch contact 122, the left-hand winding of relay 55, to battery and thence to ground. 35 As the brushes B^5 , B^6 and B^7 move over the terminal bank T, an idle trunk will finally be encountered, at which time, the brush B^3 being situated on an insulated section of commutator segment 57, and the terminal t^1 being ungrounded, the energizing circuits for both the right and left-hand windings of relay 55 will be opened, whereby relay 55 will become deenergized, and will retract its armature. 40

45 50 As a result, a circuit will be established from ground through sequence switch contact 106, the right-hand armature and normal contact of relay 52, the left-hand armature and normal contact of relay 55, sequence switch contact 114, sequence switch contact 109, the winding of motor magnet of sequence switch 100, interrupter I, battery and thence to ground. Sequence switch 100 will move its contactors into the seventh position, and in so doing interrupts the circuit just traced at sequence switch contact 114.

55 60 The valve-operating levers 112 and 113, moving the contactors of the sequence switch, will cut off the supply of compressed air and allow the brushes B^5 , B^6 and B^7 to

come to rest on the terminals t^1 t^2 and t^3 of the idle trunk. The pawl 17 will come to rest in the proper notch N of the spindle S to hold the brush carriage permanently in the selected position until released. 70

In position 7, a circuit will also be established from ground, sequence switch contact 123, the normal contact and right-hand armature of relay 55, resistance R^3 , the brush B^5 , terminal t^2 , thereby grounding 75 this terminal and marking the selected trunk as busy.

80 In position 7, the fundamental circuit, including the relay 52, is again closed, whereupon relay 52 becomes energized, and attracts its armatures. A circuit is now established between ground, sequence switch contact 106, right-hand armature and alternate contact of relay 52, the sequence switch contact 117, sequence switch contact 118, the 85 motor magnet of sequence switch 100, interrupter I, to battery, and thence to ground. Sequence switch 100 will be energized in this circuit, and will move its contactors into the eighth position, whereupon the circuit just 90 described will be broken at sequence switch contact 117.

95 In position 8, the fundamental circuit is extended to the switch selected through terminals t^1 , t^2 and t^3 over the terminal t^3 , the brush B^7 , the sequence switch contact 124, the conductor 50, apparatus of the sender to conductor 51, the sequence switch contact 103, sequence switch contact 104, resistance R^2 and ground. The next selector switch 100 will be impelled forward in a manner similar to that described in connection with the selector switch shown in Fig. 2, and when, after the first series of impulses, the sender is satisfied, the relay 52 will be deenergized. 105 A circuit is now established between ground, sequence switch contact 106, the right-hand armature and normal contact of relay 55, sequence switch contact 114, sequence switch contact 109, the motor magnet of sequence 110 switch 100, interrupter I, to battery and thence to ground. Sequence switch 100 moves its contactors into the ninth position, and in so doing opens the circuit just described at sequence switch contact 114. 115

120 In position 9, the fundamental circuit leading to the next selector switch is again completed and the circuit for relay 52 is also again completed through sequence switch contact 101. Upon the energization of relay 52, a connection is established between ground, sequence switch contact 106, right-hand armature and alternate contact of relay 52, sequence switch contact 117, sequence switch contact 118, motor magnet of sequence switch 100, interrupter I, to battery and thence to ground. Sequence switch 100 moves its contactors into the tenth position, and in so doing, opens the circuit just described at sequence switch contact 117. 130

As the second series of impulses to the selector switch beyond the one shown are sent, and when the sender is again satisfied, the relay 52 will be deenergized, whereby a circuit is established from ground to sequence switch contact 106, the right-hand armature and normal contact of relay 52, left-hand armature and normal contact of relay 55, the sequence switch contact 114, sequence switch contact 109, motor magnet of sequence switch 100, interrupter I, to battery and thence to ground. Sequence switch 100 moves its contactors into the eleventh position, and, in so doing, opens the circuit just described at sequence switch contact 114.

In the eleventh position, circuit for relay 52 is again established through sequence switch contact 101 and the sender circuit, whereupon relay 52 becomes energized and attracts its armatures. A circuit is now established from sequence switch contact 106, the right-hand armature and alternate contact of relay 52, sequence switch contact 117, sequence switch contact 118, motor magnet of sequence switch 100, interrupter I, to battery, and thence to ground. Sequence switch 100 moves its contactors into the twelfth position, and in so doing, opens the circuit just described at sequence switch contact 117.

As the contactors of sequence switch 100 move into the twelfth position, a fundamental circuit is again extended through sequence switch contact 124 to the selector switch beyond the one here shown. As another series of impulses is transmitted, and the sender is again satisfied, relay 52 is deenergized. Upon retracting its armatures, it establishes a circuit between ground, sequence switch contact 106, the right-hand armature and normal contact of relay 52, the left-hand armature and normal contact of relay 55, sequence switch contact 114, sequence switch contact 109, the motor magnet of the sequence switch 100, interrupter I, to battery, and thence to ground, whereupon sequence switch 100 moves its contactors to the thirteenth position, and in so doing, opens the circuit just described at sequence switch contact 114.

In position thirteen, a circuit is established between ground, battery, winding of relay 52, sequence switch contact 101, sequence switch contact 125, conductor 50 to a ground beyond the repeating coil of the cord circuit which is extending this connection. Relay 52 becomes energized, and in so doing, establishes a circuit from ground, sequence switch contact 106, the right-hand armature and alternate contact of relay 52, sequence switch contact 117, sequence switch contact 118, the motor magnet of sequence switch 100 to battery, and thence to ground. Sequence switch 100 moves its contactors into the fourteenth position, and in so doing,

opens the circuit just described at the sequence switch contact 117.

In position fourteen, a circuit is established between ground, sequence switch contact 116, sequence switch contact 120, the right-hand winding of relay 55 to battery, and thence to ground.

The arrangement of the system of which the circuit shown in Fig. 2 forms a part is one in which four-party selective ringing is accomplished through the selection at the first selector of one or another kind of ringing current, such, for instance, as plus pulsating or minus pulsating current, and a reversal of the line is accomplished at a selector or connector switch beyond the first. In this case selection of the plus or minus pulsating current is made by directing the brushes of the selector switch to a particular group of trunks, the conductors of which are here represented by the terminals t^1 , t^2 and t^3 . In the showing here made plus pulsating current is selected in the fifteenth position and minus pulsating current is selected in the sixteenth position. Hence, if a party whose bell responds to plus pulsating current is wanted, the ringing must occur while the selector switch is in position fifteen, and if the party whose bell responds to minus pulsating current is wanted the ringing must occur in position sixteen.

Assuming the first to be true, it will be noted that brush B^4 is driven to a point in the commutator segment 58, in which no contact is made between said brush and said commutator segment. As position fourteen is reached a circuit is established between ground, sequence switch contact 126, motor magnet of sequence switch 100, interrupter I, to battery and thence to ground, whereupon sequence switch 100 moves its contactors into the fifteenth position, and in so doing opens the circuit just described at sequence switch contact 126.

As the sequence switch moves into position fifteen, the energizing circuit for relay 55 previously described is opened at the sequence switch contact 120, and the relay 55 retracts its armatures.

In position fifteen a circuit is established from ground at the repeating coil of the cord circuit, extending this connection to conductor 50, sequence switch contact 127, normal contacts of the armature of relay 59, relay 60, armature and contact of relay 62, sequence switch contact 128, normal contact and right-hand armature of relay 52, sequence switch contact 129 to battery and thence to ground. Relay 60 is energized in this circuit, and by attracting its armatures establishes a ringing circuit from ground, upper armature and alternate contact of relay 60, brush B^7 , terminal t^8 through the next selector switch, the apparatus of the called subscriber's telephone 130

line back again to terminal t^2 , the brush B^6 , the lower armature and alternate contact of relay 60, sequence switch contact 130, the left-hand winding of relay 62 to a source of plus pulsating current.

5 The current flowing through this circuit while the bell at the called subscriber's station is ringing is not enough to energize relay 62. However, upon the removal of the receiver from its hook at the called subscriber's substation, the increase in the current flowing through the circuit just described is enough to cause the energization of relay 62, whereby the energizing circuit for relay 60 is opened at the contact and armature of relay 62, and the winding of relay 61 introduced in this circuit. Relay 61 is so designed that, upon its introduction into the energizing circuit of relay 60, the current flowing through relay 60 is reduced to such a point that it retracts its armatures. The current flowing through relay 61, however, is enough to cause it to attract its armature, thereby maintaining a circuit for itself when relay 62, in response to the deenergization of relay 60 becomes deenergized. The retraction of its armatures by relay 60 extends the talking conductors of the cord circuit, extending this call, through 25 to the called subscriber and supervisory relay 63 thereupon becomes energized.

Upon the energization of relay 63, a circuit is established from ground, armature and alternate contact of relay 63, sequence switch contact 131 to the left-hand winding of relay 55, battery, and thence to ground. Relay 55 attracts its armatures and establishes a circuit from ground, sequence switch contact 133, right-hand armature and alternate contact of relay 55, sequence switch contact 134 to motor magnet of sequence switch 100, interrupter I to battery, and thence to ground. Sequence switch 100 moves its contractors from the fifteenth position into the seventeenth position, it being noted that the circuit just described is maintained throughout the fifteenth and sixteenth positions.

The energization of relay 63 also results 50 in the establishment of a circuit between ground, the armature and alternate contact of relay 63, the winding of relay 59, the sequence switch contact 128, normal contact and right-hand armature of relay 52, sequence switch contact 129 to battery, and thence to ground. Relay 59 attracts its armature and establish an alternate circuit for the energization of relay 61 from ground, the armature and alternate contact of relay 59, relay 60, relay 61, and thence through the circuit previously traced.

Suppose now that instead of a party whose telephone bell responds to plus alternating current, that a party whose bell responds to minus alternating current is

wanted. The proper selection of trunks would have left the brush B^4 in contact with the commutator segment 58, whereupon a circuit would be established between ground, the brush B^4 , commutator segment 70 58, sequence switch contact 127, the left-hand winding of relay 55 to battery, and thence to ground.

As the contractors of sequence switch 100 passed from the fourteenth to the fifteenth 75 position, the energizing circuit for relay 55 passing through the right-hand winding of this relay would have been opened at sequence switch contact 120, but the relay would have been maintained in an energized 80 condition through the last circuit traced.

Then, as position fifteen is reached, a circuit is established between ground, sequence switch contact 133, the right-hand armature and alternate contact of relay 55, sequence 85 switch contact 134 to motor magnet of sequence switch 100, interrupter I, to battery, and thence to ground. Sequence switch 100 continues in this movement until position fifteen is passed, at which time the energizing circuit for relay 55 is opened at sequence switch contact 127, and the contractors of sequence switch 100 come to rest in position sixteen. Thereupon the previously described ringing circuit is established, with 90 the exception that instead of extending through sequence switch contact 130, the left-hand winding of relay 62 to a source of plus pulsating current, it now extends through sequence switch contact 135, the 100 right-hand winding of relay 62 to a source of minus pulsating current. The actions, thereafter, until position seventeen is reached, are the same as heretofore described.

Position seventeen is the talking position, 105 and the circuit of Fig. 2 will remain in the condition described up to this point until the completion of the conversation. At this time the hanging up of the receiver by the called subscriber results in the deenergization of the supervisory relay 63, whereupon a circuit is established from ground, the armature and normal contact of relay 63, sequence switch contact 136 to the motor magnet of sequence switch 100, the interrupter I, to battery, and thence to ground. Sequence switch 100 moves into the eighteenth position and the circuit just described is broken at the sequence switch contact 136.

In position eighteen a circuit is established from ground, sequence switch contact 106, sequence switch contact 137, the release magnet RM, battery, and thence to ground. The release magnet attracts its armature 17, thereby allowing the shaft S 120 to move downward. At the same time valve-operating levers 138 and 139 are opened to allow the ingress of compressed air into the space above the piston P, and the exhaust of the compressed air beneath 125 130.

the piston P. This results in the return of the brush carriage B to its normal position.

When such normal position is reached, a circuit is established between ground, the brush B⁴, commutator segment 64, sequence switch contact 140, the motor magnet of sequence switch 100 to interrupter I, to battery, and thence to ground. Sequence switch 100 moves its contactors into the first 10 or normal position, and upon so-doing opens the circuit just described at the sequence switch contact 140.

The hanging up of the receiver by the calling subscriber also operates a supervisory relay in the cord circuit which had been extended to this selector switch. The deenergization of this supervisory relay acts in a manner similar to that described in connection with the selector shown in Fig. 2, so that when a normal position is reached, connection between such cord circuit and the conductor 50 is broken. Also the ground which has up to this time maintained relay 53 energized is removed, and relay 53 resumes its normal position.

It may be noted that while in the sixth position, if an idle trunk had not been found the selector switch herein described would have been moved to an "over-flow" position, 30 whereupon a circuit would have been established from ground to brush B³, commutator segment 65, sequence switch contact 118, motor magnet of sequence switch 100, interrupter I, battery, and thence to ground. 35 The sequence switch would have moved directly from the sixth into the seventeenth position under the control of interrupter I, and from thence to normal through the agency of circuits established through sequence switch contact 136, and later sequence switch contact 140.

It should also be noted that should the operator handling this call abandon the same after the sequence switch 100 had reached 45 the second or some later position, she would thereby remove the ground 110 and by thus deenergizing the relay 53, establish a circuit from ground, the right-hand armature and normal contact of relay 53, sequence 50 switch contact 141, motor magnet of sequence switch 100, interrupter I, battery, and thence to ground. Through this circuit se-

quence switch 100 would be driven forward until its normal position was again reached.

What is claimed is:

1. An automatic switch having fixed circuit terminals and brushes arranged to move over and make contact with said terminals, fluid controlled means for actuating said brushes, a sequence switch having electrical contacts for controlling said automatic switch, and means carried by said sequence switch for mechanically controlling said actuating means.

2. An automatic switch having fixed circuit terminals and brushes arranged to travel over and make contact with said terminals, pneumatically controlled means for actuating said switch, a sequence switch comprising a motor magnet, a spindle arranged to be rotated by said motor magnet, a plurality of electrical contactors mounted on said spindle, and a plurality of cams for mechanically controlling said pneumatic means mounted on said spindle.

3. An automatic switch having fixed circuit terminals, and brushes arranged to travel over and make contact with said terminals, a cylinder, a piston movable in said cylinder, a connection between said piston and said brushes comprising a piston rod and a brush carriage, a source of fluid under pressure, ports for the admission and exhaust of said fluid, and valves for controlling said ports, a sequence switch comprising a motor magnet, and a spindle adapted to be rotated by said magnet, said spindle carrying a plurality of electrical contactors, and a plurality of cams for mechanically operating said valves in predetermined positions of said sequence switch.

4. An automatic switch, fixed circuit terminals, brushes arranged to travel over and make contact with said terminals, means for actuating said brushes, a sequence switch for controlling said actuating means comprising rotatably mounted electrical contactors and cams, said cams having direct mechanical control over said actuating means.

In witness whereof, I hereunto subscribe my name this 14th day of November, A. D. 1916.

JAMES L. McQUARRIE.
